[57] CLAIM

The ornamental design for a holder for filing folded matter, as shown and described.

DESCRIPTION

FIG. 1 is a perspective view of a holder for filing folded material showing my new design;

FIG. 2 is a top plan view thereof, the bottom plan view being a mirror image thereof;

FIG. 3 is a view of one longitudinal edge of the holder, which is a mirror image of the other longitudinal edge; and

FIG. 4 is a view of the end edge of the holder, which is a mirror image of the other end edge.
